Primary Examiner — Darlington Ly*Assistant Examiner* — D. Ryan Tisdale(74) *Attorney, Agent, or Firm* — Bayramoglu Law Offices LLC(57) **CLAIM**

The ornamental design for a vehicle body, as shown and described.

DESCRIPTION

FIG. 1 is a front view of a vehicle body showing our new design;

FIG. 2 is a rear view thereof;

FIG. 3 is a left side view thereof;

FIG. 4 is a right side view thereof;

FIG. 5 is a top view thereof;

FIG. 6 is a perspective view thereof; and,

FIG. 7 is a front, left perspective view thereof.

The portions of the motor vehicle shown with a ghosted effect and outside the broken lines illustrate environment and do not form part of the claimed design. The portions shown within the broken line boundaries correspond to the claimed design.

1 Claim, 7 Drawing Sheets(56)
